LIGHTING FIXTURE

Henry K. Pracht, Irwin, Pa., assignor to Pittsburgh Reflector Company, Pittsburgh, Pa., a corporation of New Jersey

Application June 28, 1941, Serial No. 400,197

2 Claims. (Cl. 240—78)

This invention relates to illuminating fixtures and, in particular, to a fixture especially adapted to utilize elongated light sources such as are pridinium, dimethyl-cyclohexyl-ammonium salts now available in the form of fluorescent tubes.

Various forms of fixtures have been proposed heretofore for utilizing luminous tubes such as the standard fluorescent tubes now available. It is an object of the invention to improve generally on such fixtures as have been known heretofore and particularly in respect to the manufacturing cost and uniformity of light distribution. A further object is to provide a fixture having an attractive appearance.

In a preferred embodiment of the invention, it comprises an elongated supporting member which may conveniently be a metal plate provided with suitable suspension means. A plurality of trough-shaped reflectors are disposed side-by-side and supported below the plate. A tubular light source such as a fluorescent tube is mounted in each reflector. End caps overlie the ends of all the reflectors at each end of the fixture. The end caps are generally normal to the longitudinal axis of the fixture. The reflectors are positioned on a curve and are substantially equidistant from the axis of the fixture. By this arrangement, the central planes of the reflectors are generally radial relative to the fixture axis so that the reflectors throw light downwardly and outwardly over a substantial area.

If the fixture is suspended below the ceiling, as contrasted with a flush-type fixture, I utilize the supporting plate as a reflector and position tubular light sources thereabove for illuminating the ceiling.

A complete understanding of the invention will result from a consideration of the following detailed description thereof and reference to the accompanying drawings illustrating a preferred embodiment and a modification.

In the drawings:

Figure 1 is a view partly in side elevation and partly in longitudinal section showing a fixture according to my invention adapted to be suspended below the ceiling;

Figure 2 is a transverse section taken substantially along the plane of line II—II of Figure 1; and

Figure 3 is a view similar to Figure 2 showing a modification.

Referring now in detail to the drawings and, for the present, to Figures 1 and 2, the fixture of my invention includes a main supporting channel 10 carried on suitable suspension hangers 55

11. In the embodiment shown in Figures 1 and 2, the supporting channel 10 serves also as a reflector, as will be described later. Its edges are bent upwardly as at 12 to provide a generally trough-shaped reflector. Beyond the portions 12, the edges of the plate 10 are bent downwardly to provide suspending flanges 13.

A plurality of trough-shaped reflectors 14, four in the embodiment illustrated, are assembled side-by-side and are supported on the inturned bottom edges 15 of the suspending flanges 13. The upper edges of the outer reflectors 14 are secured to the inturned edges 15 by screws 16. The adjacent edges of the several reflectors are received in channel strips 17 which bind them tightly together.

The particular reflectors 14 illustrated have a flat bottom 18, plane sloping lower sides 19, and plane outer edges 20 disposed at an angle to the sides 19. When the edges 20 of adjacent reflectors are in contact flatwise, as shown in Figure 2, the axes of the reflectors lie substantially in a cylindrical surface co-axial with the fixture as a whole.

End caps 21 are mounted at each end of the fixture. Each end cap overlies the ends of all the reflectors 14 and the supporting channel 10. Each end cap includes a disc 22 and a ring 23. The disc and ring are connected by circumferentially spaced straps (not shown). The discs 22 are spaced inwardly of the rings 23 and are secured by bolts 24 to supporting straps 25 depending from the ends of the channel 10. By this construction, light rays passing between the edge 35 of the discs 22 and the ring 23, from light sources to be described later, are reflected onto the exposed surfaces of the discs 22, thereby illuminating them and enhancing the appearance of the fixture.

A lower supporting channel 26 is secured to the outer reflectors 14 and ties all these reflectors into a rigid assembly. As shown, the flat bottoms of the reflectors have flatwise engagement with the sides of the channel 26. The space between the channel 10 and the plate 26 is free to accommodate control auxiliaries or the like, indicated at 27, for the light sources.

Lamp holders 28 are mounted in each of the reflectors 14 near each end thereof and luminous tubes 29 are inserted in the holders. Similar holders are secured to the supporting channel 10 and carry luminous tubes adapted to throw light upwardly. The tubes in the reflectors 14, obviously, throw light laterally and downwardly. The positioning of the reflectors causes the light

from each tube to be directed generally radially of the axis of the fixture whereby a uniform distribution of light below and on each side of the fixture is obtained.

The fixture described above, which is illustrated in Figures 1 and 2, is adapted for mounting below the ceiling. A modified construction shown in Figure 3 is adapted for mounting flush against the ceiling. In this form of the invention, the reflectors 14' are assembled in the same relation as shown in Figures 1 and 2 but are suspended from a supporting channel 10' which is substantially plane, having downturned flanges 13'. The channel 10' is supported by any suitable hangers 11' depending from ceiling outlet boxes. The fixture shown in Figure 3 includes end caps 21', generally similar to those shown at 21, except that they are segmental instead of circular. In other respects, the fixture of Figure 3 is similar to that shown in Figures 1 and 2.

It will be apparent that the invention is characterized by numerous advantages. In the first place, the fixture is highly attractive in appearance. It is adapted to provide substantially uniformly distributed illumination downwardly and laterally and, in one form, is provided with means for illuminating the ceiling. The fixture may be constructed at relatively low cost, utilizing standard parts to a large extent. A further advantage is that, when viewed from below, the fixture does not present any extensive areas which are dark, i. e., not illuminated by light from the tubular sources, except the rings 23 of the end caps which provide a pleasing contrast to the brightly illuminated remainder of the fixture. On the contrary, the fixture exhibits a substantially uniformly bright appearance; as previously explained, even the ends of the fixture are illuminated, at least so far as the discs 21 thereof may be seen.

Although I have illustrated and described but

a preferred embodiment and a modification of the invention, it will be understood that changes in the arrangement or construction and parts may be made without departing from the spirit of the invention or the scope of the appended claims.

I claim:

1. An illuminating fixture comprising a channel, an assembly of trough-shaped reflectors disposed on an arc about said channel and extending parallel thereto, said reflectors having plane bottoms and sides which are plane over at least a portion of their width, the outermost reflectors of said assembly having their bottoms in flatwise engagement with the sides of said channel and secured thereto, the plane portions of the sides of all said reflectors being in flatwise engagement with and secured to similar portions of the adjacent reflectors, a trough-shaped reflector above said assembly, means depending from said last-mentioned reflector and engaging the outermost reflectors of said assembly for supporting it, and a luminous tube disposed in each reflector.

2. An illuminating fixture comprising a channel, an assembly of trough-shaped reflectors disposed on an arc about said channel and extending parallel thereto, said reflectors having plane bottoms and sides which are plane over at least a portion of their width, the outermost reflectors of said assembly having their bottoms in flatwise engagement with the sides of said channel and secured thereto, the plane portions of the sides of all said reflectors being in flatwise engagement with and secured to similar portions of the adjacent reflectors, a trough-shaped reflector above said assembly, the edges of said last-mentioned reflector being bent down to engage the edges of said outermost reflectors and thereby support said assembly, and a luminous tube disposed in each of said reflectors.

HENRY K. PRACHT.

CERTIFICATE OF CORRECTION.

Patent No. 2,304,202.

December 8, 1942.

HENRY K. PRACHT.

It is hereby certified that error appears in the printed specification of the above numbered patent requiring correction as follows: Page 1, first column, line 4, strike out "pridinium, dimethyl-cyclohexyl-ammonium salts"; and that the said Letters Patent should be read with this correction therein that the same may conform to the record of the case in the Patent Office.

Signed and sealed this 19th day of January, A. D. 1943.

(Seal)

Henry Van Arsdale,
Acting Commissioner of Patents.
